(57) **CLAIM**

The ornamental design for a portable night light, as shown and described.

DESCRIPTION

FIG. 1 is a front, right, top perspective view of a portable night light showing our new design;

FIG. 2 is a rear, left, bottom perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof; and,

FIG. 8 is a bottom view thereof.

The stipple shading and line shading shown in the drawings illustrate a contrast in surface appearance.

The broken lines shown in the drawings illustrate portions of the portable night light that form no part of the claimed design.
